COLUMN FORM

William G. Venard, San Francisco, Calif.

Application June 10, 1946, Serial No. 675,535

1 Claim. (Cl. 25—131)

1

This invention relates to improvements in column clamping forms and has particular reference to a form for the building of concrete columns.

The principal object of this invention is to provide a form and clamp therefor which may be used over and over again, thus saving the cost of lumber and also the cost of erecting the customary nailed structure as well as the tearing down of the same.

A further object is to produce a structure wherein columns of various sizes as far as cross-sectional area is concerned may be made by using the same forms.

A still further object is to produce a device of this character which is economical to manufacture, simple to use and one which will conform to standard practices of column construction, that is as to reinforcing, pouring of concrete, etc.

Other objects and advantages will be apparent during the course of the following description.

In the accompanying drawings forming a part of this specification and in which like numerals are employed to designate like parts throughout the same,

Fig. 1 is a side elevation of a portion of a column showing two of my forms in superimposed position.

Fig. 2 is a top plan view of one of the form sections, and

Fig. 3 is a fragmentary exploded view of the parts of my form.

In the building of columns it has been customary to nail together rectangular frames which serve to hold in position upright boards to form a hollow square, into which the necessary reinforcing bars are placed and the concrete poured. Considerable time is required for the erection of these forms inasmuch as the various boards must be sawed to proper length and fitted so that there will be no leakage of concrete; then after the concrete has set the boards must be ripped off with consequent loss of the lumber due to breakage.

I have therefore devised a form which may be easily adjusted to produce hollow squares of various areas within the capacity of the form, and by placing several of these forms one upon the other a column of any desired height may thus be built. After use the various parts may be disassembled without loss of material and used over and over again.

In the accompanying drawings wherein for the purpose of illustration is shown a preferred embodiment of my invention, the numerals 5, 6, 7

2

and 8 refer to form boards of any desired size, each being provided with a pair of angularly disposed reinforcing channels, as shown at 9 and 11.

The lower end of these channels are flush with the bottom of the board but the upper ends of these extend above the tops of the boards, the purpose of which will be later seen.

These boards are assembled in end to side relation as shown in Fig. 2 so as to provide a form

10 rectangular in shape, but capable of adjustment as to size of the hollow square formed thereby. Attached to the bottom of each form board is a spacer strip which forms a notched end to accommodate the clamps to be later described.

15 This spacer is changed for columns of different cross-sectional areas and is the only part of the form which must be cut for the particular size of the column being formed.

In order to hold these boards in rectangular 20 position I provide two sets of clamping members, one positioned adjacent the lower extremity of the boards and the other adjacent the upper extremity, and as both sets of clamps are identical, but one will be described. The upper set will be described as a whole by the letter "A" and the lower set by the letter "B."

Each clamping set consists of the assemblage 25 of four (4) sets of like parts, each set consisting of an angular member 12 formed of channeled material so as to receive the end of a compression bar 13 having an elongated slot 14 which is adapted to register with a slot 16 through which passes a wedge 17, which wedge is held against accidental withdrawal by a pin 18.

30 A series of openings 19 formed in the opposite end of the bar 13 from the slot 14 permits the adjustment of the next corner angular member 12 through the medium of a pin 15. Such an adjustment is obvious and requires no further discussion.

It will therefore be apparent that by assembling 35 four angular members and their compression bars about the boards 5, 6, 7 and 8 so that they will bear against the angularly disposed channels

40 9 and 11 and by adjusting the pins 15 in the proper openings and then tightening the whole structure through the tapping of the wedges a compression will be exerted which will hold all of the boards in proper position.

45 The form thus made can be placed upon the top of a similar form, as shown in Fig. 1, and a column of any desired height may be constructed. When the column is to support a girder an individual form of the usual construction is built up

and placed upon the top of one of my forms, as shown at "C."

After the concrete in the column has set, by removing the pins 15 or by knocking the wedges loose, the various parts of the clamps may be disassembled and the boards removed and reused wherever desired.

It will thus be seen that I have produced a form clamp which accomplishes all of the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

A column form comprising a plurality of boards arranged in end-to-side relation to form an

adjustable hollow square, each of said form boards having a spacer attached to its lower portion, said spacer being of less length than the length of the form board so as to provide notched spaces between superimposed form boards, 5 whereby clamps may be engaged with the form boards, each of said form boards having angularly-disposed channels secured thereto, the lower end of said channels being flush with the bottom of the spacer and the upper end of said channels extending above the tops of said form boards.

WILLIAM G. VENARD.
